UNITED STATES PATENT OFFICE.

EUGENE S. BROWN, OF OAK STATION, PENNSYLVANIA.

GAS-LOG.

1,239,346.

Specification of Letters Patent.

Patented Sept. 4, 1917.

Application filed September 9, 1915. Serial No. 49,777.

To all whom it may concern:

Be it known that I, EUGENE S. BROWN, a citizen of the United States, residing at Oak Station, in the county of Allegheny and 5 State of Pennsylvania, have invented certain new and useful Improvements in Gas-Logs, of which the following is a specification.

This invention relates to heaters and has special reference to that class of heaters 10 known as gas logs, in which natural or artificial gas is utilized as a fuel and supplied through an opening located within a body or embedded in the material of a body composed of some non-burning material. The 15 object of the present invention is to provide a heater of the described type in which the burner proper will be hidden from view either completely or to such an extent as to not detract from the ornamental appearance 20 of the body of the device.

A further object of the invention is to provide means whereby the heat will be thrown out into the room in which the heater is located, and a further object of the invention is 25 to provide means for permitting a circulation of air within the heater so that the body of the same will not be unduly raised in temperature and will, consequently, be protected from possible burning.

30 These stated objects of the invention and other incidental objects which will herein-after appear are attained in such a device as is illustrated in the accompanying drawings, and the invention resides in certain novel 35 features which will be first fully described and then more particularly pointed out in the claims following the description.

In the accompanying drawings:

Figure 1 is a perspective view of a heater 40 embodying my present invention;

Fig. 2 is a vertical longitudinal sectional view of the same;

Fig. 3 is a transverse sectional view thereof.

As clearly shown in the drawings, the body 45 1 is so shaped as to simulate a log or section of a fallen tree and this body will preferably be composed of asbestos combined with other material of a plastic nature which may be readily molded into the desired shape. The 50 body is hollow and approximately cylindrical, a long opening 2 being provided in one portion of the side of the body to permit the escape of the heat from the burner into the room. A metallic lining 3 is provided and

this lining is spaced from the inner wall or 55 surface of the body 1, except at the lower edge of the opening 2, as shown most clearly in Fig. 3. The lining has substantially circular ends 4 which are spaced from the end walls of the body and an air space 5 is there- 60 by provided between the lining and the inner surface of the body. The upper longitudinal edge of the lining terminates at the rear of the upper edge of the opening 2, as shown at 6 in Fig. 3, and to the said edge of the 65 lining I secure a metallic hood or shield 7 which is connected with the upper edge of the opening 2 by spaced lugs or ribs 8 whereby the air circulating between the inner surface of the body and the lining will be per- 70 mitted to escape into the room. The burner 9 is located immediately adjacent the inner edge of the hood or shield 7 and extends longitudinally of the body of the heater, being provided with a row of tips 10, which 75 may be of metal or some refractory compo- sition, as will be readily understood. The gas is supplied to the burner by an inlet pipe 11 which extends through the back portion of the heater and between the end of the 80 same and the end of the lining, as shown clearly in Figs. 2 and 3, and is connected with the burner by a coupling 12 in the usual manner. The burner tips 10 will be very 85 small and will be directed downwardly and forwardly so that jets of flame extending from the tips will not protrude through the opening 2 of the device in a dangerous or unsightly manner but will be barely visible, so that they will have the appearance of 90 small tongues breaking through the shell of a log. A series of openings 13 are formed through the body of the device in rear of the lining and near the bottom thereof so as to admit air to the space 5, and the lower por- 95 tion of the outer surface of the heater is flattened, as shown at 14, so as to provide a steady rest therefor and relieve the supply pipe 11 of the strain of holding the heater in a position in which it may be placed.

100 It will be noted, more particularly upon reference to Fig. 3, that the burner is located very slightly below the horizontal plane of the upper edge of the opening 2 so that it will not be visible to the casual observer 105 when the device is in use, and the appearance of a burning hollow log will be created. It will also be noted that the burner is located

immediately adjacent the inner edge of the hood 7 so that the heat generated at the burner will be thrown downwardly and forwardly and escape through the longitudinal opening 2 of the heater. The metallic lining 3 will be of polished copper or other serviceable material so that the heat waves emanating from the burner will be thrown into the room and the heater will have a highly ornamental appearance. The lining will also become heated so that the air in contact therewith will rise in temperature and a circulation of air currents be set up through the openings 13 and around through the heater to escape at the upper front end of the lining between the ribs or lugs 8 and through the opening 2 so that the air in the room containing the heater will be very quickly raised to the desired degree.

20 My device is exceedingly simple in its construction and may be produced at a low cost. When in use it will be found highly efficient for the purposes for which it is designed.

25 Having thus described the invention, what is claimed as new is:

1. A heater comprising a substantially cylindrical casing having its opposite ends closed and provided in one side thereof with a longitudinal opening, a lining member eccentrically mounted within the casing and having an opening registering with the longitudinal opening in said casing, said lining defining an intermediate substantially crescent-shaped heating chamber, there being draft openings formed in the casing and communicating with the heating chamber, a burner extending longitudinally of the lining member, and a deflector secured to the lining member at said burner and having its outer longitudinal edge provided with spaced lugs secured to the inner wall of the casing near the upper wall of the longitudinal opening therein and defining spaced passages communicating with the heating chamber whereby to permit the heated air from said chamber to pass through the passages between the lugs into a room.

50 2. A heater comprising a substantially cylindrical casing having its opposite ends closed and one side thereof provided with a longitudinal opening, a lining member eccentrically mounted within the casing and defining a substantially crescent-shaped heating member, one longitudinal edge of the lining member being secured to the casing at the lower wall of the opening therein and the other edge of the lining member being spaced from the interior of the casing and terminating short of the upper longitudinal wall of the opening in said casing, there being draft openings formed in the casing at the rear thereof and communicating with the crescent-shaped heating

chamber, a burner disposed within and extending longitudinally of the lining member, and a deflector having its intermediate portion secured to the free end of the lining member and one longitudinal edge thereof arranged near the burner, the other longitudinal edge of the deflector being provided with spaced lugs rigidly secured to the inner wall of the casing at the upper wall of the longitudinal opening therein and defining spaced passages communicating with the interior of the crescent-shaped heating chamber.

3. A heater comprising a substantially cylindrical casing having its opposite ends closed and one side thereof provided with a longitudinal disposed opening, a lining member eccentrically mounted within the casing and having its opposite ends closed and one longitudinal edge thereof secured to the casing at the lower wall of the opening therein and its other edge spaced inwardly from the upper wall of said opening and also from the inner wall of the casing, said lining member defining an intermediate substantially crescent-shaped heating chamber, there being draft openings formed in the casing near the bottom thereof and communicating with the heating chamber, a burner disposed within the lining member and extending longitudinally thereof, and a deflector extending the entire length of the lining member and having its intermediate portion secured to the lining member above the burner and its forward longitudinal edge provided with spaced lugs rigidly secured to the inner wall of the casing at the upper wall of the longitudinal opening therein and defining spaced passages communicating with the crescent-shaped heating chamber.

4. A heater comprising a substantially cylindrical casing having its opposite ends closed and one side wall thereof provided with a longitudinal opening, the bottom of the casing being flat and the rear wall thereof provided with spaced draft openings, a substantially cylindrical lining member eccentrically mounted within the casing and defining a substantially crescent-shaped heating member with which the draft openings communicate, one longitudinal edge of the lining member being secured to the casing at the lower wall of the longitudinal opening therein and the other longitudinal edge of the lining member being spaced from the inner wall of the casing and from the upper longitudinal wall of said opening, the opposite ends of the lining member being closed and spaced from the adjacent ends of the casing to form end chambers, a burner extending longitudinally within the lining member and through both of the end walls thereof, a fuel conductor disposed within one of the end chambers and con-

nected with the burner, and a deflector having its intermediate portion secured to the upper edge of the lining member and its rear edge curved rearwardly and down-
wardly in the path of the burner, the forward longitudinal edge of the deflector being provided with spaced upstanding lugs

secured to the inner wall of the casing at the upper wall of the longitudinal opening therein and defining spaced passages communicating with the crescent-shaped heating chamber. 10

In testimony whereof I affix my signature.
EUGENE S. BROWN. [L.S.]
